WORK FOLDING ATTACHMENT FOR
SEWING MACHINES

Jonas F. Imberman, Los Angeles, Calif.

Application June 19, 1946, Serial No. 677,857

4 Claims. (Cl. 112—147)

1

My invention relates to a work folding attachment which is particularly adapted for use with sewing machines of the double stitch type and which are used for hemming the edges of two strips of work material simultaneously, said strips being used in the manufacture of curtains and other articles.

The primary object is to automatically inturn and guide two strips of material with their folded edges engaged below the feed presser foot of a sewing machine so as to relieve the operator from the necessity of guiding the strips by hand. Another object is the saving of hand labor and the provision of means by which the operation of sewing including the guiding and directing the material into the machine is simplified and made easy. Another object is adjustability of the parts of my improved apparatus whereby strips of work material varying in width are accomplished. Another object is the production of a readily foldable structure which in cooperation with the front section of the sewing machine table upon which the sewing machine head is connected can be swung outwardly into extended position or inwardly into operative position to facilitate access to the working parts of the sewing machine head. Among further objects are maximum simplicity of construction and effectiveness in use.

In the accompanying drawings forming part of this specification, Fig. 1 is a front perspective view showing my improved folding attachment applied to a sewing machine; Fig. 2 is a front elevation of the folding machine attachment when removed from the sewing machine; Fig. 3 is a plan of the structure shown in Fig. 2; Fig. 4 is a perspective view of a detail illustrating the outwardly swung position assumed by the folding machine attachment when the front hinged section of the sewing machine table is opened; Fig. 5 is a front elevation of one of the adjustable combined folding and guide plates when removed from my improved folding machine attachment; Fig. 6 is a plan of the structure shown in Fig. 5; Fig. 7 is a section taken on the line 7—7 of Fig. 6, and Fig. 8 is a section of a detail taken on the line 8—8 of Fig. 3.

In the drawings A represents an ordinary multiple needle type sewing machine head which has the usual laterally spaced needles 10 and 11 on the usual needle bar 12 and the needle plate 13. The double threads 14 and 15 are looped and threaded through the needles in the usual manner. This type of machine head is adapted to sew and hem the longitudinal edges

of two strips of work material simultaneously when fed through the machine.

The sewing machine head is mounted on a suitable work table B, the front housing section 15 of which, as shown is right angular in cross section. The lower edge of the front side 16 is hinged at 17 to the base 18 so that said housing section can be swung outwardly to permit an operator gaining access to the usual various adjustments in the front lower portion of the sewing machine and for threading the loopers, all of which is well known and in common use.

My improved work folding attachment C is mounted on the upper side 16' of the housing section by hinges 20, two of which are secured to the end angle supports 21 of my improved attachment. Another hinge 22 on the upper side 16' and in line with the end hinges is secured to the forward ends of the supporting plate 23. The supporting plate 23 normally rests horizontally flat on the upper side 16' of the front housing section 15 and is secured at the opposite ends rigidly to the lower surfaces 25 of the upper arms 24, thus cooperating with the end angle supports to form a rigid skeleton frame. Normally the depending arms 25 of the end angle supports are secured in downwardly and outwardly slanting position by their upper

30 end portions and plate 23 resting on the upper side of the housing member when the latter is raised and assumes closed position as shown in Fig. 1. A pair of upwardly spaced horizontal shafts 26 and 27 are secured by their ends in parallel relation longitudinally on the outwardly depending arms 25.

Two apron plates 30 and 31 for assisting in guiding two strips of work material into the sewing machine are supported by upper flanges 40 32 and 33 in longitudinally adjustable position on the supporting plate 23 by screw and slot connections 34, the normal position of the apron plates being substantially in the plane of the downwardly and rearwardly slanting position assumed by the end supporting arms 25. The corresponding end portions of the apron plates are formed with a pair of upwardly extending substantially parallel inturning folding guide members 35 and 36 for two work strips such as 50 D and E. Each guide member has a reverse guide channel, the two channels 37 and 38 (Fig. 3), opening outwardly apart to admit the inner edges of said strips of work material and turn their edges inwardly in the reverse guide chan-

2

material are guided with their edges inturned in alignment with the needle plate to be hemmed simultaneously by the usual operation of the sewing machine head.

Arranged in cooperation with the inturning folding guide members 35 and 36 are respectively longitudinal guide channel plates 39 and 40 which engage and guide the outermost side edges of the two strips of work material. These plates 39 and 40 are slidably held by their lower ends on the lower shaft 27 by sleeves 41 and are secured in adjusted position longitudinally on the upper shaft 26 by the collar and set screw members 42 to accommodate any width of work material strip. In this manner the guide channel members 39 and 40 can be set to guide and accommodate strips of any desired width and to cause the inturning of their companion inner edge portions so that the sewing machine will hem the inturned inner edges of both strips of work material simultaneously. The fasteners 42 preferably have their operable set screws directed upwardly at a slightly inclined angle as shown which tends to prevent the screws working loose when subjected to the vibration produced by the sewing machine head.

To retain the strips of work material in inturned folded flat position as they are fed forwardly into engagement below the presser foot of the sewing machine head, two presser plates 45 and 46 are provided, one for each strip of work material. These presser plates are hinged freely along their upper edge portions to swing upwardly on a horizontal shaft 47, said shaft being mounted upon upstanding bosses 43 which are secured rigidly to the supporting plate 23 of the apron frame structure. The free end portions of the presser plates are regulated in height above the supporting plate 23 to provide a free passage forwardly for the strips of work material by the adjustable lock bolts 49. These plates press downwardly by their own weight to releasably hold the strips of work material flat on the supporting bar 23 as they progress forwardly.

In accordance with the patent statutes I have described the principles of operation of my invention together with the construction thereof which I now consider to represent the best embodiment thereof, but I desire to have it understood that the construction shown is only illustrative and that the invention can be carried out by other means and applied to uses other than those above set forth within the spirit of the invention and the scope of the following claims.

I claim:

1. A work strip folding attachment for a double needle sewing machine having a presser foot with which the needles cooperate and a work table with a hinged front section adapted to swing out-

wardly and downwardly, comprising an apron frame hinged at its upper end to the upper portion of said front section of the table to swing outwardly from the work table and normally supported in outwardly and downwardly slanting position for assisting in guiding two strips of work material into said machine, and a pair of inturning folders mounted upon said apron frame for simultaneously inturning corresponding edges 5 of the strips of work material when fed over said apron frame in operative position below said presser feet to be stitched by said needles.

2. In a structure as defined in claim 1, the edge inturning folders being adjustably supported laterally on said apron frame to regulate the inturned folded edges of the strips of work material in juxtaposition to the presser foot and the reciprocable needles of the sewing machine.

3. In a structure as defined in claim 1, each 20 of said edge inturning folders having a cooperating guide for the outer edge of each strip of work material, said guide being adjustably supported in accord with the width of the strip of work material which has its edge inturned and 25 folded.

4. A work piece folding attachment for a double needle sewing machine having a presser foot with which the needles cooperate and a work table with a hinged front section adapted to swing 30 outwardly and downwardly, comprising an apron frame hinged at its upper end portion on the upper portion of said front section of said table to swing outwardly clear of the table and normally supported in outwardly and downwardly 35 slanting position for assisting in guiding two strips of work material into operative position into said machine, a pair of inturning folders mounted upon said apron frame for simultaneously inturning contiguous edges of two strips of work material 40 when fed over said apron frame to be stitched by said needles, and presser plates freely hung on said apron frame and directed downwardly upon the strips of work material as they leave the folders and are engaged by said needles.

JONAS F. IMBERMAN.
